(57) **CLAIM**

I claim the ornamental design for a cell phone case with magnifying lens, as shown and described.

DESCRIPTION

FIG. 1 is a top, front, right side perspective view of the cell phone case with the magnifier lens in a retracted position.

FIG. 2 is a bottom, back, right side perspective view of the cell phone case with the magnifier lens in a retracted position.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a top, front, right side perspective view of the cell phone case with the magnifier lens in an extended position.

FIG. 10 is a bottom, back, right side perspective view of the cell phone case with the magnifier lens in an extended position.

FIG. 11 is a front elevational view thereof.

FIG. 12 is a rear elevational view thereof.

FIG. 13 is a left side elevational view thereof; and,

FIG. 14 is a right side elevational view thereof.

The claimed design is shown with a symbolic break in its length. The appearance of any portion of the article between the break lines forms no part of the claimed design.

All broken lines depict unclaimed environment; the broken lines form no part of the claimed design.
